UNITED STATES PATENT OFFICE.

FRANK WILCOMB, OF NORRISTOWN, PENNSYLVANIA, ASSIGNOR, BY MESNE ASSIGNMENTS, TO HEMPHILL MANUFACTURING CO., OF PAWTUCKET, RHODE ISLAND.

KNITTING-MACHINE.

1,100,806.

Specification of Letters Patent. Patented June 23, 1914.

Application filed February 4, 1909. Serial No. 476,024.

To all whom it may concern:

Be it known that I, FRANK WILCOMB, citizen of the United States, residing at Norristown, Pennsylvania, have invented certain new and useful Improvements in Knitting-Machines, of which the following is a specification.

My present invention is an improvement upon that disclosed in application for Letters Patent of the United States, filed by me Nov. 19, 1906, Patent No. 1,054,067, dated Feb. 25, 1913, and it consists in the features and combination and arrangement of parts hereinafter described and particularly pointed out in the claims.

In the accompanying drawings, Figure 1 is a sectional view through my improved knitting head. Fig. 2 is a plan view of a portion of the knitting head. Figs. 3 to 10 are views of details.

1 is the needle cylinder, 2 the independently sliding sinkers, 3 the independently sliding web holders and 4 and 5 the cams for the sinkers and web holders respectively. 25 The presser plate or wheel 6 operates within the needle circle, and forces the needles 7 outwardly beyond their normal plane against the inner edge of a presser ring 8, in the pressing action, for casting off the old 30 loops. This ring is interposed between the sliding sinkers and sliding web holders and affords plain ground and hardened bearing surfaces therefor, a cover for the web holders, and as it has upwardly and downwardly 35 grooved parts 9, 10, Fig. 7, it affords guiding means for both the sliding sinkers and web holders near their nose ends. These sinkers and web holders are also guided in their beds 11, 12, near their outer ends. These 40 beds are attached together at 13 and their attached portions rotate in the channel of the fixed frame ring 14, which is supported on posts, Fig. 1, and is separated from the needle cylinder by a free space 15 which is 45 bridged by the web holders, the nose ends of which find an accurate bearing on the ground and hardened plain upper edge of the needle cylinder. The sinkers are further guided by grooves on a cover ring 13' 50 engaged by the upper edge of the sinkers. This prevents the sinkers from tilting over out of plumb and the guiding means described renders it possible to employ a large number of needles, sinkers and web holders 5 to the inch for fine gage work. This cover

plate 13 is simply laid on the sinkers needing no fastening means and the same is true of the encircling presser ring 8, no special or accurate fitting to the adjacent parts being necessary, these plates being self centering on the radial sinkers and web holders respectively, and being carried around in the revolution of the machine by engagement with the web holders and sinkers which rotate said plates by their engagement therewith. The cover plate also protects the sinkers from accumulations of lint, dust or oil, and this plate in turn is covered by a thin sheet metal cover 16 which is fixed in position and protects the movable cover plate 13 on which lint might otherwise collect and be rolled up into balls by passing under the fixed arms 17 of the presser wheels, which would eventually find their way into the needles and sinkers and produce a "smash up". 75 Accumulations of dust, lint or bunches are also free to pass out from the needles beneath the edge of the presser ring and fall away from the fabric through the free space 15 beneath the web holders. 80

As above stated, the sliding web holders are guided in grooves near their nose ends formed in a depending flange or rim of the encircling presser ring 8. This depending rim performs a double function, that of 85 guiding the web holders by their upper edges, thus preventing tilting and therefore rendering it possible to employ a large number to the inch for fine gage work, and also affording downwardly projecting teeth located between the web holders against which the beard is pressed and held for a long period in its pressed position by the presser wheel or plate, until the hook of the spring needle has passed through the old loop sufficiently far to insure the casting off of the old loop and prevent mispressing. Guiding slots for the web holders, at their nose ends, are also provided by a ring 12' Fig. 9 separate and distinct from the cylinder but secured thereto. This ring has its slots cut slightly below the upper edge of the cylinder so that it serves merely to hold the web holders against lateral displacement or tilting. 95

The plain upper and lower surfaces of the 105 presser ring may be accurately ground and hardened to afford guiding surfaces for the sinkers and web holders and the same is true of the upper edge of the cylinder and by this the web holders and sinkers will be 110

held more accurately to the desired level than is possible where reliance is had only upon the bottoms of milled slots.

The sliding web holders present the advantage that they can be readily removed and replaced by moving them radially inwardly or outwardly as the case may be, they being simply slid through the space 18, Fig. 2 in their cams. The web holders 10 coat with a clearer plate 19 in controlling the fabric, said plate being on the inside of the needle row adjacent the presser wheel or plate, with which it co-operates. It is carried by an arm 20 fixed at 21 to the fixed 15 head or cam ring 14' secured at 14" upon the fixed ring 14. The clearer plate is bent or curved to conform to the top of the cylinder. It smoothes down the fabric passing under it and removes any bunches or 20 lint and prevents it from reaching the presser plate or wheel and causing a jam there, and furthermore it removes all obstructions liable to cause bending or jamming of sinkers, needles or web holders, and 25 facilitates the work of renewing the knitting operation, when for instance, a part of the work has run off the needles or a hole has occurred in the fabric the said plate forcing the fabric downwardly and away from 30 the needles even though a take up is not used.

The clearer plate has an edge inclining downwardly and forwardly in the direction of movement of the fabric, when used in a 35 machine of the rotary cylinder type, as in the present illustration of my invention, whereas in the other or fixed cylinder type of machine it may be said to incline backwardly in relation to the direction of rotation of itself and other parts, but in both cases its downwardly inclined edge extends to such a point in relation to the presser plate or wheel as to smooth down the fabric and clear it of all obstructions, 45 preventing them from reaching the presser device.

This clearer plate has an upward extension 22 lying close to the needles to push into alinement any bent needle, and the 50 edge of the plate next to the fabric or needle advancing in the arrow direction Fig. 3, curves downwardly as above stated to direct any lumps or lint down and away from the presser wheel, needles, sinkers and 55 web holders. The thread feeding eye 23 is directly adjacent this plate and a support 24 is supported, by the arm 20, on the inside of the needle row to support the hook end of the needle when it is receiving the thrust 60 of the sinkers in measuring off the thread for the new loops, this support truing up any needles which may be slightly bent and insuring even loop lengths. This support 65 has a flared or curved end at 25 to receive any needles which may be slightly bent.

This support lies between the forward end of the clearer plate and the presser. The presser wheel or plate is carried by a block 26 slideable on the arm 17 and carried by a screw stem 27 by which the block together with the presser wheel may be adjusted manually, it being automatically adjustable or yielding by a spring 28 bearing in the block. The screw stem is slidably mounted in its bearings. The screw stem 75 may be locked in adjusted position by a detent 29 pivoted to the arm 17 and engaging notches in a finger wheel 30 fixed on the screw stem. The spring 28 may be adjusted as to tension by turning the finger wheel 80 31 which is also locked in adjusted position by the detent 29, which is pressed by the spring 31'. The presser wheel may be held retracted to discontinue its use or the use of a single feed in a multiple feed machine, 85 by simply drawing on the finger wheel 30 until disengaged from its detent and then turning the finger wheel so that the solid part thereof between the notches will engage the end of the detent, thus holding 90 the presser device out of action.

The sinker cam of each feed is adjustable individually by the compound bolt 32 passing through the split block 33 which is secured at 34 to the ring 35. The compound bolt 95 engages the block 36 which by a screw 37 passing through the radial opening 38 is connected with the sinker cam 4 pivoted at 40. By turning the compound bolt the sinker cam may be adjusted and the bolt 10 may be held by drawing the split parts of the block 33 together by the screw 33'. There is one of these adjusting devices for each feed, the machine being described having 12 feeds, and for adjusting all of the 10 sinker cams simultaneously the ring 35 is turned and because of the approach of the center of the point or screw 34 to the same radial line in which the point or screw 37 lies, the point 37 must move inwardly 110 along the said radius, it being clear that the point 34 can have no radial movement.

For moving the ring 35 a hole is provided at 41 and three holes at 42 so that by using a lever having pins to enter the hole 41 and 115 either one of the holes 42 the ring may be turned, and when in the desired position it may be held by a set screw 43 passing through one of the arms 17 to the presser supports. The web holder cam may be adjusted by the screw 47.

The sinker cam ring 14' is formed in sections as shown in Fig. 2, one section for each feed. Each section has its own cams, presser, clearer plate, thread guide, needle 125 support, and sinker cam adjusting means and the ring 35 is also formed in sections one for each feed. By removing a cam ring section the sinkers are rendered accessible for removing and replacing. The sections of 130

the ring 35 are connected together by the links 43* held by the screws 44, and dowels 45, and by the construction described any sinker cam section may be removed from the machine and replaced without destroying the adjustment of any of the parts carried thereby. The web holder cam ring is also formed in sections 46, one of which is shown in Fig. 10 and these sections are removably held by the bolts 47 to the fixed frame or cam ring.

It will be observed that the web holder cam ring being attached to the lower or inner side of the main frame ring is practically as readily accessible as the sinker cam ring. The two sectional cam rings lie at the top and bottom of the frame ring respectively, with the sinkers and web holders between them and any section of either ring 20 may be readily removed without dismantling the machine or removing outer parts as both rings are exposed and accessible.

Fig. 2 shows only one section of the cam ring completely equipped with presser, 25 clearer, thread, guide, and needle support, but each section is to be provided with these devices. For convenience of illustration the sinker cams and web holder cams are shown in Fig. 2 in dotted lines on adjacent sections 30 of the cam rings.

At the point where the pressing is done the web holder cam is provided with a recess or receding edge at 5* so that the web holders may recede and thus prevent cutting 35 the fabric when the needles are pressed outwardly from their normal plane against the presser ring. I prefer to make this cam with its outer or back edge as shown to positively retract or move outwardly the web 40 holders at the pressing point.

The construction described wherein the running parts move in grooves or chambers enables the parts to be freely bathed in oil without danger of any oil reaching the fabric on the inner side of the cylinder. The 45 free space 15 intervening between the cylinder and the cam ring contributes largely to this as any oil passing out from the groove 12* in which the attached portions of the sinker and web holder beds travel will fall down through the space 15 and the nose end of the web holders will be kept entirely free of oil.

It will be observed that the sinker covering ring 13' is undercut, that it is provided 55 with guide grooves or teeth only at its inner portion, the undercut part being in length greatly in excess of the travel of the sinkers, so that oil is not carried from the cam to the shallow groove and thence to the nose of the 60 sinker and fabric. The sinker is also undercut and so is the presser ring forming channels for instance at 48 of greater width than the length of travel of the sinker or web holder so that the travel of these parts will

fail to carry the oil across the channels. 65 The presser ring while provided with the channels on both faces, has the plain flat, upper and lower faces for the guidance of the sinkers and web holders.

The needles are operated by jacks 48* 70 slidably in slots 49 of a needle cage, the lower ends of the metal strips 50 forming the cage being set in a ring 51 secured to the revolving base ring 52 to which the needle cylinder is attached. Both the needle and 75 jacks are guided both by the cylinder grooves and by the cage grooves.

The cage is braced by a ring 53 at its top. The needle cams 54 are carried by sections 55 of a cam ring secured to the fixed base 56 80 by screws 57 Figs. 1 and 6. Any section can be removed and the needle jacks removed through the space thus afforded below the cage ring 53, and having removed the jack 85 its needle may be removed by thrusting the needle upwardly until its lower end is above the ring 53 and then drawing it outwardly and downwardly. The cage is low in height for this purpose.

The shanks of the needles run in the 90 grooves of both the cylinder and the cage and the needles are thus prevented from tipping. The needles and jacks are not fixed to each other but engage each other removably, so that the jacks can be removed first 95 and then the needles.

Each needle cam is adjusted by a screw 58, Figs. 1 and 5, having a flange 59 engaging a notch in the post 60 to which the cam is secured. The flange of the screw is notched 100 so that the operator can tell just how far he is adjusting the cams and make it agree with the adjustment of the other cams, a spring 61 engaging the notches successively as the screw is turned and thus enabling the operator to determine how many points or steps he is adjusting the cam. The post 60 is pressed upwardly by a spring 62 acting on a pin 63 having a flanged head engaging a 110 notch in the post 60. The cam can thus be 110 adjusted up or down by operating the same screw 58. Many new effects flow from the use of the outer presser ring combined with the sliding web holders as will appear from the foregoing and appended claims. 115

The rotating parts are arranged to have running fits with the parts within them or which they surround, so that as the machine heats up the rotating part in expanding will either expand equally with the part on which it runs, or will expand more rapidly if of less mass of metal and thus loosen up as it were instead of sticking or running harder upon the part on which it fits. This is illustrated as an instance between the rotating web holder bed and the inner part at 12 of the fixed ring on which the bed has a 120 close running fit.

It will be seen that the sinker and web holder-beds run in an oil pocket or groove in the fixed ring or head 14, and the same is true of the base flange or gear of the cylinder. The fixed base ring 52 has an oil channel 67. Any oil which overflows into the grooves 68 is carried back by the channel 67 to the oil pocket 69.

The invention is not limited to a rotary cylinder machine. The rotary parts are driven through the vertical shaft 64 and the gears 65, 66.

The free space 15 is of particular importance in connection with the use of web holders. As is well known by those skilled in the art, lint dust and oil accumulate within the web holder guide grooves, in ordinary knitting practice, requiring frequent dismantling of so much of the machine as will enable the operator to gain access to and remove the packed oil-soaked lint. This packing of the lint, dust and oil in the grooves is due to the fact that the web holders are constantly in contact with the fabric and are rubbing the fabric at each reciprocation with a comparatively slow motion. The fabric itself prevents the escape of lint from the work end of the web holder and the groove, as the groove is covered thereby. Furthermore the web holders are always in engagement with the cylinder grooves at their nose ends and this adds to the undesirable effect of lint accumulation. In order to overcome this difficulty I have provided an open or free space between the cylinder and the web holder bed which is bridged by the web holders and which will permit the escape of lint, dust and oil from the web holders and allow it to fall away from the machine, and at the same time this bridged arrangement of the web holders prevents oil from reaching the work end of the web holders, the needles, and the fabric.

I claim as my invention:

1. In combination in a spring needle knitting machine, a cylinder, needles, sliding sinkers and sliding web holders, an inner presser, an outer presser ring interposed between the sliding sinkers and web holders and having upwardly projecting teeth for guiding the sinkers and downwardly projecting teeth for guiding the web holders, substantially as described.

2. In combination in a spring needle knitting machine with the needles, sliding web holders and sinkers, the inner presser, and the outer presser ring having upwardly and downwardly projecting guiding teeth and plain bearing surfaces one on the top and the other on the bottom for the sinkers and web holders, substantially as described.

3. In combination in a circular spring needle knitting machine a cylinder, needles, radial sliding sinkers, and radially sliding web holders, a toothed outer presser ring,

laid on to the web holders and held and centered by its lower teeth engaging the same and affording by its upper teeth guides for the sinkers and a covering ring having teeth for guiding the sinkers and laid thereon to be held and centered thereby, substantially as described.

4. In combination in a spring needle knitting machine having needle grooves, needles, an inner presser to press the needles outwardly, an outer presser ring, web holders sliding below the said presser ring, and for which said presser ring serves as a cover, and supported by the needle cylinder, and a web holder cam with means for supporting the same independently of the cylinder and arranged with a free space below the web holders and between the cam support and the cylinder, said presser ring extending across the said free space, substantially as described.

5. In combination in a spring needle knitting machine, a cylinder, needles, an inner presser, an outer presser ring, web holders sliding against the under side of the presser ring, and an outer bearing for the running parts, said presser ring and web holders being in contact at one point and having a space between them at another point to prevent oil from reaching the fabric, substantially as described.

6. In a spring needle knitting machine having sinkers and web holders, a needle cylinder, a frame ring encircling the cylinder with a free space between, supporting posts for the frame ring spaced apart, sinker and web holder beds carried by the frame ring, a sectional cam ring for the sinkers exposed on the top of the machine, and a sectional cam ring for the web holders arranged in the free space on the inner side of the frame ring, said sectional cam ring being accessible for removal, substantially as described.

7. In combination in a knitting machine, the cylinder, needles, sliding sinkers, and cams, an adjusting ring therefor and a connection between the ring and each cam, having its connecting points with the ring and the cam normally out of the same radial plane, but to be moved toward and from said plane by operating the ring for adjusting the cam, substantially as described.

8. In combination in a circular knitting machine a cylinder, needles, sinkers, cams therefor, a sectional plate carrying said cams, sectional adjusting means detachably connected together with means for locking said sectional adjusting means in position, substantially as described.

9. In combination in a circular knitting machine, needles, a cylinder, web holders, a presser ring exterior to the needle circle, a presser interior in respect to the needle circle, and a clearer operating on the inside of the needle circle to smooth down the fabric.

on the inner side of the cylinder adjacent the interior presser, said clearer having a downwardly extending edge inclined toward the presser, substantially as described.

5 10. In combination in a circular knitting machine, needles, a cylinder, web holders, a presser ring exterior to the needle circle, a presser interior in respect to the needle circle, and a clearer operating on the inside of the needle circle to smooth down the fabric on the inner side of the cylinder adjacent the interior presser, said clearer having a portion inclined to the path of the needles and lying close thereto to even the same, substantially as described.

11. In combination in a spring needle knitting machine a cylinder, needles, a presser, a spring pressed support therefor, the manually operated adjusting device, com-

20 prising a screw a notched disk thereon and a pawl to engage either of the notches to lock the presser or to engage the portions between the notches to hold the presser retracted, substantially as described.

25 12. In a knitting machine the grooved needle cylinder, a surrounding cage, slotted to receive the needle shanks and jacks which are also guided in the grooves of the cylinder and cage and a cam ring having a removable portion to permit the lateral removal of the jacks through the laterally open slots of the cage, said needles and jacks being separable from each other by a lateral movement of the jack in respect to the needle through the 35 slotted cage, leaving the needle to be removed over the cage top, substantially as described.

13. In a knitting machine the grooved needle cylinder a surrounding cage grooved 40 to receive the needle shanks, jacks separable

from the needles by a lateral movement while the latter remain in their grooves, said jacks being guided by the cylinder and cage grooves, the jacks being removable through the grooves of the cage and the 45 needles over the top of the cage, substantially as described.

14. In combination in a knitting machine, a cylinder, needles, a needle cam, the post, the screw having the notched flange engaging 50 the post, a spring engaging the notched flange and a spring for pressing the post upwardly, substantially as described.

15. In combination in a spring needle knitting machine, the needles the inner 55 presser, the outer presser ring, the web holders located outside the needle row and the web holder cam also outside the needle row and having a recess opposite the pressing point to permit the web holders to recede 60 outwardly when the pressing is done.

16. In combination in a spring needle knitting machine, the outer presser ring, the inner presser, the web holders and the web holder cam, having a recess opposite the 65 pressing point to permit the web holders to recede when the pressing is done and having a portion for positively withdrawing the web holders at the pressing points.

17. In combination the inner presser, the 70 outer pressing ring undercut on both faces and sinkers and web holders sliding on said faces, and means for guiding and operating the sinkers.

In testimony whereof, I affix my signature 75 in presence of two witnesses.

FRANK WILCOMB.
